UNITED STATES PATENT OFFICE.

THEODORE W. KLOMAN, OF PARK RIDGE, NEW JERSEY.

INTERNAL-COMBUSTION ENGINE.

1,319,398.

Specification of Letters Patent.

Patented Oct. 21, 1919.

Application filed June 10, 1918. Serial No. 239,088.

To all whom it may concern:

Be it known that I, THEODORE W. KLOMAN, a citizen of the United States, residing at Park Ridge, in the county of Bergen and 5 State of New Jersey, have invented a certain new and useful Improvement in Internal-Combustion Engines, of which the following is a specification.

The invention relates to engines having a 10 plurality of cylinders, and more particularly to the valves controlling the admission and exhaust of such cylinders.

The object of the invention is to provide a valve of the rotary type in which the distribution of fuel gas from the carburetor to the several cylinders shall be uniform, and the cooling effect of such gas efficiently utilized in lowering the temperature of such valve, and in general, to obviate the difficulties and avoid the objectionable features 20 usually attending the employment of valves of this type.

The invention consists in certain novel features of construction, and arrangements 25 of ports and passages by which the above objects are attained, to be hereinafter described and claimed.

The accompanying drawings form a part 30 of this specification and show the invention as applied to a four-cylinder engine of the four cycle type.

Figure 1 is a vertical section taken axially of the cylinders, and partly in elevation.

Fig. 2 is a corresponding horizontal section 35 through the valve casing, showing the valve in plan view, the plane of section being indicated by the line 2—2 in Fig. 1.

Figs. 3, 4, 5 and 6 are vertical sections, taken on the line 3—3 in Fig. 1 and partly 40 in elevation, showing the relative positions of the valve and its ports and passages in each of the four cylinders as conditioned in Fig. 1, or may be understood to show one of the cylinders and the valve as conditioned 45 for each of the four cycles successively.

Similar letters of reference indicate the same parts in all the figures.

A¹, A², A³ and A⁴ are the cylinders of the engine arranged vertically side by side in 50 alinement and preferably in pairs, each pair controlled by a cylindrical valve B¹ and B² both coupled to rotate and operate together as a single valve extending across the top of the cylinders with its axis intersecting the axial lines of the cylinders and inclosed in the cylinder heads A serving as

the valve casings which are closed at the ends by the valve casing heads B. A stem or shaft B³ extends through one head B and carries a sprocket wheel and chain B⁴ by 60 which the valve B¹ is rotated from the main shaft, not shown, or other moving part, and the two valves are coupled together at B⁵ to move as one.

Each valve is hollow and closed at the 65 ends and each has four inlet ports marked C¹, C², C³ and C⁴ in one, and C⁵, C⁶, C⁷ and C⁸ in the other, extending through the shell of the valve to the interior thereof, and four exhaust passages D¹, D², D³ and D⁴ in one, 70 and D⁵, D⁶, D⁷ and D⁸ in the other, formed as deep grooves or pockets on the cylindrical exterior of the shell.

Fuel gas is received through a pipe C from the carburetor, not shown, and delivered through the branches C⁹ and C¹⁰ to the manifolds C¹¹ C¹² each forming a chamber c¹ c² having a long opening or port c³ c⁴ extending nearly the entire length of each valve and having a width of approximately 80 one fourth of the circumference of the valve, so that one quarter of the entire superficies of the valve is bathed in the fuel gas at all times when the engine is running. These openings c³ c⁴ are crossed by narrow diagonally arranged webs or bridges C¹³ C¹⁴ serving to join the margin of the openings and stiffen the valve casing. 85

The inlet ports C¹ C² in the valve B¹ are 90 diametrically opposite near one end, and the inlet ports C³ C⁴ of the same valve are opposite each other near the other end of the valve and are located at a right angle to the first pair. The inlet ports C⁵ C⁶ and C⁷ C⁸ in the valve B² are similarly arranged but 95 at an angle of forty-five degrees to the corresponding inlet ports of the valve B¹.

On the interior of the valves are swells corresponding to the spiral exhaust pockets or recesses on the exterior of the valves, permitting such pockets to be of sufficient depth and area to allow the spent gases to escape freely therethrough, and one end of each pocket is in circumferential alinement with the inlet ports of the valve and with the 100 cylinder port, and the other end, which is advanced or offset about an eighth of the circumference, extends to a central zone on the valve in alinement with a central exhaust port leading to an exhaust manifold or other 105 duct located on the opposite side of the valve casing from the inlet manifolds. The ex- 110

haust port or chamber is shown as located below the axial line of the valve, and the pockets are so shaped as to lead from the intake ports of the pair of cylinders inwardly 5 to the exhaust port, maintaining such communication alternately at each end of the valve during the periods in which the pockets are passing the cylinder ports. The pockets forming each pair are diametrically 10 opposite each other and separated the proper distance each from the adjacent inlet ports.

The valves rotate in the direction indicated by the arrow in Fig. 3 and it will be noted that each one-eighth turn of the valve 15 presents an inlet port at the openings c^3 c^4 for an intake of fuel gas, and that such presentation takes place alternately at the ends of each valve-section.

The exhaust pockets or recesses D^1 D^2 are 20 located at one end of the valve B^1 and D^3 D^4 are at the opposite end. The pockets D^5 D^6 and D^7 D^8 occupy corresponding positions on the valve B^2 . When either of the exhaust pockets is presented to the port at the top of 25 a cylinder its advanced end is presented to the centrally located exhaust port D^9 or D^{10} in the valve casing, which ports lead to an exhaust manifold or pipe D^{11} and thence escape as usual. There is no position of the 30 valves in which the pockets can establish communication between the chambers c^1 c^2 and the exhaust ports D^9 D^{10} .

The four cylinders in Fig. 1 show the conditions and relative positions of the valves and pistons for a complete cycle, and the 35 transverse sections in Figs. 3, 4, 5 and 6 show the same. The piston in the cylinder A^1 is at the mid-stroke downward and is taking in fuel gas through its cylinder port a^1 which 40 is received from the chamber c^1 through the inlet port C^3 , traverses the interior of the valve B^1 to the inlet port C^1 and thence delivered to the cylinder A^1 . The opposite inlet port C^2 is sealed by the valve casing as is 45 also the inlet port C^4 , and the exhaust pockets D^1 D^2 and D^3 D^4 are either sealed or are in idle communication with the chamber c^1 or exhaust port D^9 , and the cylinder port a^2 is sealed by the valve.

50 The piston of the cylinder A^2 is at the end of its upstroke with its charge of gas fully compressed and ready for ignition.

The valve B^2 as before stated is advanced forty-five degrees relatively to the valve-section 55 B^1 , and the piston of its cylinder A^3 is at the end of its downward or intake stroke and beginning to compress; the cylinder port a^3 is sealed by the valve B^2 , the inlet port C^5 is sealed by the valve casing, and 60 the inlet port C^6 is beginning to receive gas from the chamber c^2 . At the opposite end of the valve B^2 , in the cylinder A^4 the piston is at the mid-stroke upward driving out the exhaust through the cylinder port a^4 and 65 exhaust pocket D^7 , the advanced end of

which is in communication with the exhaust port D^{10} , and the inlet ports C^7 and C^8 are sealed by the valve casing while the exhaust pocket D^8 is idle passing the chamber c^2 .

It will be noted that the fuel gas enters 70 the valves B^1 B^2 alternately from each end and traverses the interior of each in reaching the cylinder ports at the time of intake; the gas travels always the same distance and under the same conditions of area so that 75 short paths to the intake are avoided and the cylinders are each supplied uniformly; and that the interior surfaces of the valves are bathed in a practically continuous current of cool fuel gas flowing alternately in opposite 80 directions through the valve and distributed uniformly, serving to maintain a low temperature. The exterior of the valves is cooled by the fuel gas flowing into and from the chambers c^1 c^2 in which approximately 85 one fourth of the entire surface of each valve is exposed, and the rotation of the valves present new surfaces successively.

Lubrication is effected by supplying a suitable lubricant to the fuel gas and is thus 90 delivered in the chambers c^1 c^2 and distributed with the gas over the exposed constantly changing surfaces of the valves.

In the arrangement shown having two inlet ports for each of the four cylinders and 95 two exhaust pockets for each, the valve is timed to make one complete revolution for four revolutions of the crank-shaft, consequently the rate of speed of the valve is low and the advantages due to such low valve- 100 speed are attained.

As many valves as required may be coupled to rotate together and control the admission and exhaust of a corresponding number of pairs of cylinders, or the valve-sections may be formed in a single casting with partitions dividing the interior into the desired number of chambers each having its inlet ports and exhaust pockets.

By employing a single cylinder port both 110 for intake and exhaust and thus eliminating the separate exhaust port usually required, the area of valve surface exposed to the pressures of compression and explosion is correspondingly lessened with a correspond- 115 ing reduction of valve-friction and wear against the opposite wall of the valve casing.

Parts of the engine not specially described may be understood to be as usual or 120 of any approved construction. Water jackets for the valve casing and cylinders are shown and may be varied as found desirable.

I claim:—

1. In an internal combustion engine, a plurality of cylinders set side by side each having a cylinder port, a rotatable hollow cylindrical valve having inlet ports leading 130 from the exterior to the interior thereof and

matching to said cylinder ports, arranged to receive fuel gas through one of said inlet ports, cause such gas to traverse the interior of such valve in direct contact with the 5 walls thereof, and deliver such gas through the other of said inlet ports to one of said cylinder ports.

2. In an internal combustion engine, a plurality of cylinders set side by side each 10 having a cylinder port, a rotatable hollow cylindrical valve having inlet ports leading from the exterior to the interior thereof and matching to such cylinder ports, arranged to receive fuel gas alternately through said 15 inlet ports, cause such gas to traverse the interior of said valve in direct contact with the walls thereof alternately in opposite directions, and deliver such gas through said inlet ports alternately to said cylinder 20 ports.

3. In an internal combustion engine, a plurality of cylinders set side by side each having a cylinder port, a hollow cylindrical valve closed at the ends and having a radial 25 inlet port at each of said ends leading from the exterior of said valve to the interior thereof, and matching to such cylinder ports, arranged to receive fuel gas through one of said inlet ports and deliver such gas 30 after traversing such valve in direct contact with the walls thereof through the other of said inlet ports to one of said cylinder ports, and means for rotating said valve.

4. In an internal combustion engine, a 35 plurality of cylinders each having a cylinder port, a valve casing having a fuel gas chamber therein, a hollow cylindrical valve rotatable in said casing, closed at the ends and having a radial inlet port at each of 40 said ends, said inlet ports arranged to register alternately with said chamber and said cylinder ports, to admit such gas alternately at the ends of said valve to the interior thereof, cause such gas to traverse the interior of such valve in direct contact with the walls thereof, and deliver such gas alternately to said cylinder ports at the opposite ends of said valve, and means for rotating said valve.

5. In an internal combustion engine, a 50 plurality of cylinders set side by side, each having a cylinder port, a valve casing having a fuel gas chamber therein, a hollow cylindrical valve rotatable in said casing, said valve closed at the ends and having a radial inlet port at each of said ends, said inlet ports arranged to register alternately with said chamber and said cylinder ports, to admit such gas alternately at the ends of 55 said valve to the interior thereof and deliver such gas alternately to said cylinder ports at the opposite ends of said valve, the latter having exhaust pockets on its exterior arranged to register with said cylinder 60 ports, and means for rotating said valve.

6. In an internal combustion engine, a plurality of cylinders set side by side, each having a cylinder port, a valve casing having a fuel gas chamber therein, a hollow cylindrical valve rotatable in said casing 70 and having inlet ports at its ends arranged to register with said chamber and with said cylinder ports, an exhaust port in said casing between said inlet ports, exhaust pockets on the exterior of said valve, each arranged 75 to register at one end with said cylinder ports and at the other end with said exhaust port, and means for rotating said valve.

7. In an internal combustion engine, a plurality of pairs of cylinders arranged side 80 by side in a single series, each cylinder having a cylinder port, a series of hollow cylindrical valves, one for each pair of cylinders, extended longitudinally of said series of cylinders and coupled to rotate as one, and 85 each closed at the ends, a casing inclosing said series of valves and having a fuel gas chamber for each pair of cylinders exterior to its valve, each of said valves having a radial inlet port near each end, said inlet 90 ports arranged to register alternately with the cylinder ports of an adjacent pair of cylinders and admit fuel gas from one of said chambers through one of said inlet ports, cause such gas to traverse the interior 95 of such valve in direct contact with the walls thereof, and deliver such gas through the other of said inlet ports to the cylinder port of the cylinder at the opposite end of said valve, said series of valves arranged to deliver such gas successively to the several 100 cylinders of the series, and means for rotating said series of valves.

8. In an internal combustion engine, a plurality of cylinders set side by side, each 105 having a cylinder port, a valve casing, a hollow cylindrical valve closed at the ends and rotatably mounted in said casing and having a radial inlet port near each end, a fuel gas chamber in said casing extending longitudinally of said valve and partially inclosing it, said inlet ports arranged to register alternately with said chamber and with cylinder ports and adapted to receive such gas from said chamber at one end of said 110 valve, traverse such gas through the interior of said valve in direct contact with the walls thereof and deliver it at the other end of said valve to one of said cylinder ports, such gas in such traverse serving to cool the interior of said valve, and the gas in said chamber serving to cool the exterior of said 115 valve.

9. The valve described comprising a hollow cylinder closed at the ends and having 120 near each end a radial inlet port for fuel gas received from the exterior of said valve, and pockets on the exterior of said valve near its opposite ends, having one end of each pocket in circumferential alinement with 125

said inlet ports and the other end of said pockets advanced circumferentially and extended longitudinally of said valve to coincidence on a circumferential zone on said 5 valve between said inlet ports.

10. The valve described comprising a hollow cylinder closed at the ends and having near each end a pair of oppositely located radial inlet ports for fuel gas received from the exterior of said valve, the inlet ports at one end advanced circumferentially relatively to the others, and pairs of exhaust pockets on the exterior of said valve, arranged oppositely to each other diametrically and the pair at one end of said valve advanced circumferentially relatively to such pair at the opposite end of said valve, one end of each of said pockets in circumferential alinement with the adjacent pair 15 of inlet ports, and the other end of each of said pockets advanced circumferentially and extended longitudinally of said valve to coincidence on a circumferential zone on said 20 valve between said pairs of inlet ports.

11. In an internal combustion engine, a 25 pair of cylinders arranged side by side each having a single cylinder port serving both for intake and exhaust, a hollow cylindrical valve extended longitudinally of said pair and closed at the ends, a casing inclosing 30 said valve and having a fuel gas chamber exterior to said valve, and an exhaust port, said valve having oppositely located radial inlet ports at each end and exhaust pockets on the exterior of said valve between adjacent inlet ports, the latter arranged to register with said cylinder ports and deliver fuel gas to such cylinders through said inlet ports and the interior of said valve, said 35 pockets arranged to register with said cylinder ports at one end of said pockets and advanced circumferentially and extended longitudinally of said valve at the other end of said pockets, to register with said exhaust port, and means for rotating said valve. 40

In testimony that I claim the invention above set forth I affix my signature. 45

THEODORE W. KLOMAN.
